COMBINED BATHTUB AND SHOWER UNIT

Edmund F. Humphries, Jr., Tulls Creek Road,
Moyock, N.C. 27958

Filed May 21, 1971, Ser. No. 146,002

Term of patent 14 years

Int. Cl. D23—02

U.S. Cl. D23—49

FIG. 1

FIG. 2

FIG. 3

FIG. 4

FIG. 5

FIG. 6

FIG. 1 is a perspective view taken from the front and one side of a combined bathtub and shower unit showing my new design;

FIG. 2 is a perspective view taken from the rear and side opposite that shown in FIG. 1;

FIG. 3 is a section on 3—3 of FIG. 1;

FIG. 4 is a section on 4—4 of FIG. 1;

FIG. 5 is a section on 5—5 of FIG. 1; and

FIG. 6 is a section on 6—6 of FIG. 1.

The broken line representation of fixtures in FIG. 4 is for purposes of illustration only.

I claim:

The ornamental design for a combined bathtub and shower unit, as shown and described.
